FREDERICK GEOFFREY LEES JOHNSON, OF WESTMINSTER, LONDON, ENGLAND,
ASSIGNOR TO VICKERS LIMITED, OF WESTMINSTER, LONDON, ENGLAND.

SHELL-FUSE.

1,322,191.

Specification of Letters Patent. Patented Nov. 18, 1919.

Application filed November 11, 1918. Serial No. 262,055.

To all whom it may concern:

Be it known that I, FREDERICK GEOFFREY LEES JOHNSON, a subject of the King of Great Britain, residing at Vickers House, 5 Broadway, Westminster, in the county of London, England, have invented certain new and useful Improvements in or Relating to Shell-Fuses, of which the following is a specification.

10 This invention relates to shell fuses of the time type and has for its chief object to provide a fuse in which the timing can be effected with accuracy, the slow burning composition being protected from atmospheric and other disturbing agencies.

According to this invention the effective length of a bent column of slow burning composition, preferably inclosed in a lead or other soft metal sheath or tube, is determined by a cutter angularly adjustable relatively to the tube or columns and operated by the set back on firing the shell from the gun. The setting of the fuse is therefore not actually completed before the firing so 25 that the fuse column remains undisturbed until the shell is fired. The cutter may be operated by the set back of an inertia member which at or toward the end of the cutting operation fires a percussion cap and 30 ignites the end of the fuse, ignition therefore taking place only after cutting.

In the preferred arrangement, the cutter simultaneously severs two fuse columns or lead tubes, which may be superposed one 35 upon the other or may be arranged in spiral form lying side by side, in which latter case the cutter must be adjusted in setting the fuse to move upon a spiral path. For this purpose the cutter may be mounted to slide 40 upon a radial pin and may be guided by a spiral channel or a wall in a spirally arranged holder for the fuse. The cutter is formed with a depression or channel at one side, which is arranged to afford communication between the severed ends of the two 45 fuse columns, so that the flash from one column, when the severed portion has been consumed, passes into the severed end of the second column, which burns in the reverse direction, until the flash passage leading to the magazine is reached, the shell being then exploded.

A fuse of this kind can be completely inclosed so as to be protected from atmospheric action and we may arrange to inclose

the fuse columns in a chamber or dome and utilize the set back on firing the shell from the gun to open the said chamber to the atmosphere. The device may also be constructed so as to cause a suction in the chamber when the shell is in flight, withdrawing the products of combustion as they are generated from the fuse composition. 60

In order that the said invention may be clearly understood and readily carried into effect, we will describe the same more fully with reference to the accompanying drawings, in which:

Figure 1 is a longitudinal section through a shell fuse constructed in accordance with this invention; 70

Figs. 2 and 3 are cross sections respectively on the lines $x-x$ and $y-y$ of Fig. 1.

Fig. 4 is a detail view showing the securing of the ends of the fuse columns; and 75

Fig. 5 is an end view of a dome or chamber containing the fuse.

A is the fuse body carrying the central stem a and screwed at a' in the end of the shell. B, B' are two columns of slow burning composition inclosed in lead tubes and placed one above the other. The upper column B terminates at one end in the cap b while one end of the lower column is made with the downward extension b' passing through the fuse body A and leading to the fuse magazine C in the base of the body. The two columns B, B' are shown of circular form. D is the time ring, in the grooves d of which the columns B, B' are supported. E is the dome inclosing the fuse and closed at its outer end by the cap F. G is the knife for severing the tubes or columns B, B' and carried on the bracket g belonging to the time ring D. H is the inertia member or ring mounted to slide upon the stem a and formed with a flange h provided with the overhanging lip h' which engages under the nose g' of the knife G. 85 90 95

The knife G is adjustable by means of the time ring D through the greater part of a circle between the lines $z-z$ (Figs. 2 and 3) indicating respectively the beginning and end of a fuse column. The fuse composition is removed from the cap end of the upper tube B so as to provide for zero timing, the flash from the cap igniting the fuse composition at about the position indicated by the upper line z . The ends of the tube B, B' are clamped in place by the blocks b^2 and 105 110

the screws b^2 securing the blocks to the fuse body A. The knife G is pivoted at g^2 on the end of the bracket g and is formed at one side with the recess or depression g^3 which, 5 when the knife is operated to cut the two tubes or columns B, B', provides for direct communication between the upper and lower tubes at the point of section, so that when the portion of the composition in the upper 10 tube which is adjacent to the cap b has burnt out the flame is led directly to the corresponding position to the second or lower tube B' and the flame passes backward through the reverse column of composition 15 until it reaches the tube extension b' of the lower tube when the flame ignites the magazine C and the shell is fired.

The inertia member H is of disk form with a central conical boss h^2 arranged to 20 strike and fire the detonating cap b of the upper fuse tube only at about the end of the movement of the knife G, so that ignition of the fuse cannot take place until the tubes have been placed in communication with one 25 another. This is arranged for by the proportions of the inertia member H and the form of the knife, the nose g' of which lies in the recess formed by the flange h and lip h' of the inertia member, the lip securely 30 holding the knife in inoperative position until the set back of the inertia member drives the knife backward, the lip h' bearing upon the curved back g^4 of the knife.

The inertia member H is normally held 35 in position by the saddle spring h^3 placed inside the plug ring h^4 screwed in the upper end of the member H, the device being held in position on the stem a by means of the cap F, which is screwed upon the outer reduced end a^2 of the stem and is fixed in position by a cross pin or other locking device.

On firing the shell the set back of the member H bends down the saddle spring h^3 45 and the member is then free to operate the knife G, driving the latter back so as to sever the fuse tubes B, B' and place them in communication through the recess g^3 of the knife, whereupon the conical boss h^2 of the 50 member H strikes the fuse cap b and ignites the initial end of the fuse composition which thereupon burns at the predetermined rate until the portion of the column which has been severed by the knife has been consumed. The knife itself prevents the flame 55 reaching the continuation of the first column but directs it through the recess or depression g^3 into the severed end of the second column B', which burns in the reverse direction to its end, the time of burning being reduced according to the proportion of the tubes which has been cut out of action by the knife. As the angular adjustment of the 60 knife is effected by the time ring D, which is 65 free to turn around the tubes B, B' lying

freely in the grooves d, the effective length of the fuse columns can be adjusted from zero position up to a maximum indicated by the second or lower line z.

The dome E forms a complete inclosure 70 for the fuse and is made to provide substantial internal volume so as to keep the conditions during the burning of the fuse composition as constant as possible and to avoid the development of high pressures. It is 75 very desirable to protect the fuse from atmospheric action until the shell is fired and for this purpose the dome E forms a complete and air tight inclosure opened automatically to the atmosphere on firing the 80 shell from the gun. This is effected by the set back acting upon small lead or other plugs e placed in conical or outwardly expanding apertures e' in the end of the dome immediately below the cap F. The cap F 85 extends at its lip f slightly beyond the dome surface and an annular channel f' is formed inside the lip which, as shown in Fig. 1, extends over the outer part of the plugs e, the under surface of the cap inside the channel 90 projecting over the inner edges of the plugs so as to prevent any danger of their accidentally coming out of the conical or expanded apertures.

When the shell is fired from the gun the 95 set back of the lead or other plugs is sufficient to cause them to force their way inwardly through the apertures e' and to open the interior of the dome to the atmosphere through the channel f' of the cap. The passage of the shell through the air at high 100 velocity causes considerable suction behind the lip of the cap and consequently a substantial reduction of pressure is produced inside the dome, so that the air and the gases 105 generated by the burning fuse composition are withdrawn. This reduction in pressure reduces the rate of burning of the fuse and improves the constancy of conditions existing during burning so that not only is a greater time obtained for a given length of 110 composition but the timing of the fuse can be effected with greater accuracy owing to the continuous withdrawal of the products of combustion as they are formed.

What I claim and desire to secure by Letters Patent of the United States is:—

1. In a time fuse for shells, a protected column of fuse composition, a relatively adjustable cutter, means for operating the cutter by the set back on firing the shell from a gun, so as to sever the column of composition, a fuse magazine and means for affording operative communication between the severed end of the column and the magazine. 115

2. In a time fuse for shells, a protected column of fuse composition bent into a curve, an angularly adjustable cutter, means for operating the cutter to sever the column by the set back due to firing the shell from a 120

130

gun, a fuse magazine and means for affording operative communication between the severed end of the column and the magazine.

3. In a time fuse for shells, two protected 5 columns of fuse composition, a relatively adjustable cutter adapted to sever the columns and at the same time to provide communication between the severed portions of the two columns, and means for operating the cutter 10 by the set back due to firing the shell from a gun.

4. In a time fuse for shells, a protected column of fuse composition, a relatively adjustable cutter and an inertia member 15 engaging with the cutter and positively holding it in inoperative position until the shell is fired from the gun, when the set back of the inertia member drives the cutter backward to sever the fuse column.

20 5. In a time fuse for shells, two protected columns of fuse material bent in superposed circles, a relatively adjustable cutter adapted to sever the columns and to provide communication between the severed ends of the 25 columns, and means for operating the cutter by the set back due to firing the shell from a gun.

6. In a time fuse for shells, a pair of 30 curved columns of fuse material, lying side by side, and a cutter adapted to be operated by the set back on firing the shell from a gun, which cutter is provided with a depression in its face forming a communication between the severed ends of the two columns.

35 7. In a time fuse for shells, a protected column of fuse composition, an adjustable pivoted cutter formed at the back with a projecting nose, and an inertia member of flanged disk form, which engages the nose 40 to hold the cutter normally in inoperative position, the said inertia member, by the set back on firing the shell from a gun, driving the knife backward to cut the fuse column.

8. In a time fuse for shells, a protected 45 column of fuse composition having a percussion cap at one end, a relatively adjustable cutter, and an inertia member adapted to hold the cutter normally in inoperative position and to drive it backward to cut the said 50 column by the set back on firing the shell from a gun, a part of the inertia member

striking the cap to ignite the column when the latter has been severed by the cutter.

9. In a time fuse for shells, a pair of superposed circular columns of protected fuse 55 composition, a rotatable time ring having channels in which the said columns lie, a pivoted cutter mounted upon the said time ring, and an inertia member engaging the said cutter and adapted to hold it normally 60 in inoperative position, and to drive it backward to sever the columns by the set back on firing the shell from a gun.

10. In a time fuse for shells, a fuse body 65 having a central stem, a pair of protected columns of fuse composition, a rotatable time ring having channels in which the said columns lie, a percussion cap at one end of one of the columns, an extension at the corresponding end of the second column leading 70 through the fuse body to the fuse magazine, a cutter carried by the time ring, an inertia member mounted to slide upon the central stem of the fuse body and means for holding the inertia member in position on the 75 stem until the shell is fired from a gun, when the set back frees the inertia member and causes it to operate the cutter, which severs the columns of fuse composition.

11. In a time fuse for shells, a chamber 80 normally closed to the atmosphere and containing the fuse, and means by which the chamber is opened to the atmosphere by the set back on firing the shell from a gun.

12. In a time fuse for shells, a normally 85 closed chamber containing the fuse and having an aperture leading to the atmosphere, and a plug of soft material closing the said aperture but adapted to open it by the set back on firing the shell from a gun. 90

13. In a time fuse for shells, a chamber containing the fuse and normally closed to the atmosphere, means by which the said chamber may be opened to the atmosphere by the set back on firing the shell from a 95 gun, and means by which the flight of the shell causes suction in the interior of the chamber and discharges the gases into the atmosphere.

In testimony whereof I affix my signature. 100

FREDERICK GEOFFREY LEES JOHNSON.
